UNITED STATES PATENT OFFICE.

EDWIN L. WHITE, OF BROOKLYN, NEW YORK.

LIGHTING-FIXTURE.

1,270,081.

Specification of Letters Patent. Patented June 18, 1918.

Application filed August 28, 1917. Serial No. 188,548.

To all whom it may concern:

Be it known that I, EDWIN L. WHITE, a citizen of the United States, residing at the borough of Brooklyn, county of Kings, in 5 the city and State of New York, have invented an Improvement in Lighting-Fixtures, of which the following is a specification.

My invention relates to lighting fixtures, 10 and particularly to holders for light transmitting shades or bowls of the character illustrated and described in my application filed May 19th, 1917, Serial No. 169,610, the present invention being an improvement 15 upon that device. Holders of this character prior to my said earlier invention had been made comprising a ring-shaped top adapted for connection with a socket cover or shell provided with set screws for clamping the 20 ring, and with two downwardly extending oppositely bowed arms connected at their upper ends to the ring by solder or rivets and at their lower ends in the same manner to a dish-shaped bottom, which holders were 25 placed inside the bowl whose bottom rested within a cup secured to the inner dish-shaped member. My prior application above referred to relates to providing a strong and secure attachment of the arms to the top 30 ring, and an unbreakable connection between the lower ends of the arms in such manner as to render the employment of the inner dish-shaped member unnecessary, and in my present invention I prefer to employ 35 the same connection for the lower ends of the arms, although it will be apparent that the old style of bottom connection may be used, the object of my present invention being to provide means for connecting the 40 holder directly to a lamp-socket dispensing with a cover for the socket and the set screws required where the upper ends of the arms of the holders have been attached to a ring connected to a socket cover or shell.

45 In the accompanying drawing:

Figure 1 is an elevation of the upper portion of one of the arms.

Fig. 2 is a similar view of the other arm.

Fig. 3 is a plan view of Fig. 1.

50 Fig. 4 is a plan view of Fig. 2.

Fig. 5 is a plan view of the coupling ring.

Fig. 6 is a cross section of the coupling ring on the broken line 6—6 Fig. 5.

Fig. 7 is an elevation of a lamp socket.

55 Fig. 8 is an elevation partly in section showing the parts assembled as in use, and

Fig. 9 is a fragmentary section in enlarged size to more clearly illustrate the holder as clamped to the socket.

Similar reference characters indicate like 60 parts throughout the several views.

10 and 11 denote two oppositely disposed and more or less bowed arms each provided at its upper end with a horizontal semi-circular extension 12, these extensions being 65 oppositely curved on the respective arms.

Each arm for a predetermined distance below the extension is preferably bent vertically in a straight line and somewhat flattened, the semi-circular extensions also being preferably flattened; the ends of these extensions meet forming a ring. These curved portions are preferably made integral with the arms, but may be made separate and attached in any suitable manner. 70

The lower ends of the arms 10 and 11 are 75 preferably bent and secured within recesses in the hub 13 as shown and described in my aforesaid application.

14, indicates a bowl the bottom of which 80 rests within or upon the cup 15, which is provided with a central hole for the passage of a screw 16 upon the projecting end of which is screwed a nut 17 whereby the bowl is held in position and the cup secured to the 85 arms. The screw may be made integral with the hub if desired.

18, denotes a lamp-socket of the ordinary character, provided at its lower part with an annular rib 19. 90

20, indicates the coupling ring by means of which the globe holding device is connected to the lamp-socket 18.

This ring is of sheet metal with outwardly curved lower part, and is preferably provided with an inturned annular flange 21 at the top, and annular rib 22, at the bottom to give rigidity and strength. 95

Between the top of the ring and the bottom rib thereon, a plurality of spaced U-shaped cuts are made, forming a plurality of 100 spaced spring fingers 23.

Each of these fingers is provided on its inner surface with a transverse shoulder or projection 24. These projections are formed 105 by bending the fingers inwardly at or near their longitudinal center and then outwardly, thus leaving the lower ends of the fingers curved outwardly as shown.

In connecting the bowl holding device to 110 the socket, the ring 20 is first placed over the lower end of the socket 18. This end of

the socket is then passed between the semi-circular extensions 12 on the upper ends of the arms 10 and 11 there being sufficient spring in the arms to allow the annular rib 19 to pass and enter the recesses 26, one of which is preferably provided in the inner surface of each arm immediately below the semi-circular extension thereon, after which the ends of the semi-circular extensions are again brought together with their under surfaces seated upon the top of the rib 19. The ring 20 is then pressed downward over the semi-circular extensions 12, the spring fingers 23 being compressed in so doing until the projections 24 pass the extensions 12, when they spring inwardly, the projections 24 catching under the bottom edges of the semi-circular extensions locking them together with the lamp-socket clamped between them; the rib 19 on the socket preventing any possibility of the socket being pulled out until the coupling ring is released.

25, indicates an electric lamp.

25 I have illustrated my improvement in connection with a suspended lamp-socket, but it is also applicable to ceiling lights or upright or portable fixtures without change where such fixtures are already installed.

30 I claim as my invention:

1. A device for supporting a bowl in lighting fixtures, comprising a divided ring, an arm depending from one end of each ring section, a member to which the lower ends of said arms are attached, said divided ring being adapted to surround the lower part of a lamp socket, and means for locking the same in such position.

40 2. A device for supporting a bowl in lighting fixtures, comprising a divided ring, an arm depending from one end of each ring section, a member to which the lower

ends of said arms are attached, said rings being adapted to surround the lower part of a lamp socket, and a clamping member provided with a plurality of spaced fingers having projections to catch under said ring sections.

45 3. The combination in a lighting fixture of a lamp socket provided with an annular bead adjacent its lower end, a device for supporting a bowl comprising a divided ring, an arm depending from one end of each ring section, a member to which the lower ends of said arms are attached, said ring being adapted to surround the lamp socket above the said annular bead and rest thereon, and a coupling member surrounding said ring and provided with a plurality of spring fingers having projections which 50 spring over and catch under said ring sections and hold the same in position upon the socket.

4. The combination in a lighting fixture of a lamp socket provided with an annular 55 bead adjacent its lower end, a device for supporting a bowl comprising a divided ring, an arm depending from one end of each ring section and provided with a recess on its inner surface adjacent said section, a member to which the lower ends of said arms are attached, said ring sections surrounding the socket above and seated upon said annular bead which is received in said recesses in the arms, and a clamping member surrounding said ring sections and provided with a plurality of spaced fingers having projections which 60 spring over and catch under said ring sections whereby said bowl supporting arms are held in position 65 upon the socket.

Signed by me this 24th day of August, 1917.

EDWIN L. WHITE.
